(57) **CLAIM**

The ornamental design for a fence with overhang structure, as shown and described.

DESCRIPTION

FIG. 1 is a perspective view of the fence with overhang structure;

FIG. 2 is a detailed view of mesh thereof;

FIG. 3 is a view from one side thereof;

FIG. 4 is a front view thereof;

FIG. 5 is a view from an opposing side thereof;

FIG. 6 is a rear view thereof;

FIG. 7 is a plan view from above thereof; and,

FIG. 8 is a plan view from below thereof.

The broken lines in FIGS. 1 and 2 depict the limits of the enlarged view and form no part of the claimed design.
